UNITED STATES PATENT OFFICE

99,510

DESIGN FOR A HEATER

Bertrand B. Kahn, Cincinnati, Ohio, assignor to
The Estate Stove Company, Hamilton, Ohio, a
corporation of Ohio

Application August 5, 1935, Serial No. 57,958

Term of patent 7 years

To all whom it may concern:

Be it known that I, Bertrand B. Kahn, a citizen of the United States of America, residing at Cincinnati, in the county of Hamilton, State of Ohio, have invented a new, original, and ornamental Design for Heaters, of which the following is the specification, reference being had to the accompanying drawing, forming a part thereof.

The figure is a perspective view of the heater showing my new design.

As shown, the heater, embodied and constructed to incorporate the design, comprises a body casing supported by short legs. At the top of the casing is a cover portion, rounded at the corners, and just below which is a horizontally extending decorative strip of polished metal

which, like the small decorative plate provided at the upper portion of the casing front, is in pleasing contrast with the darker color of the main body.

The other side of the heater is substantially the same in appearance as the one shown. The back of the heater is substantially the same in appearance as the front except that it does not have the small decorative plate near the top and there is the conventional opening for the flue connection.

I claim:

The ornamental design for a heater, substantially as shown and described.

BERTRAND B. KAHN.
